UNITED STATES PATENT OFFICE.

GROSVENOR P. ROBINSON, OF SUMMIT, NEW JERSEY, ASSIGNOR TO LIGHTING STUDIOS COMPANY, OF NEW YORK, N. Y., A CORPORATION OF NEW YORK.

DESIGN FOR A PORTABLE LAMP.

Application filed January 8, 1924. Serial No. 8,278. Term of patent 7 years.

To all whom it may concern:

Be it known that I, GROSVENOR P. ROBINSON, a citizen of the United States, residing at Summit, in the county of Union and State of New Jersey, have invented a new, original, and ornamental Design for a Portable Lamp, of which the following is a specification, reference being had to the accompanying drawing, forming part thereof. The figure is an elevation of a portable lamp showing my new design.

I claim:

The ornamental design for a portable lamp, as shown.

GROSVENOR P. ROBINSON.
